TUBE FORMING MACHINE

Carl Stockstrom, St. Louis, Mo.

Application November 4, 1935, Serial No. 48,686

7 Claims. (CL 93—82)

This invention relates generally to tube-forming machines, and more specifically to an improved machine for forming tubes made from flexible materials, such, for instance, as paper, cellulose tissue, celluloid, fabric, rubber, etc., the predominant object of the invention being to provide an improved machine of this type which includes adjustable means, which may be adjusted even while the machine is running if this be necessary, so as to regulate the width of tubing formed by the machine.

All of the previously known tube-forming machines with which I am familiar included each a number of sets of tube-forming elements, which had to be maintained on hand for producing tubing of various widths with the aid of the machine. In other words, if tubing of a certain width was to be produced on one of these previously known tube-forming machines, a certain set of forming elements would be associated with the machine, and when it was desired to produce tubing of a different width the set of forming elements previously used would have to be removed from the machine, and another set of forming elements adapted to produce tubing of the desired width would have to be associated with the machine.

The invention disclosed herein eliminates the need for a number of sets of forming elements for producing tubing of various widths, this desirable end being attained by providing the improved machine with forming elements which are permanently associated with the machine, and which are adjustable so as to provide for producing tubing of different widths even while the machine is running, if this be required. Thus in the use of the improved machine there is no necessity to perform the time-consuming tasks of replacing the forming elements every time it is desired to change the width of the tubing being formed, but instead it is merely necessary for the operator of the machine to rotate a hand wheel, in a manner to be hereinafter explained, to change the adjustment of the forming elements in order to produce tubing of the desired width.

Fig. 1 is a side elevation of the improved machine.

Fig. 2 is a plan view of the machine illustrated in Fig. 1.

Fig. 3 is an enlarged longitudinal section taken on line 3—3 of Fig. 2.

Fig. 4 is a cross section taken on line 4—4 of Fig. 3.

Fig. 5 is an enlarged cross-section taken on line 5—5 of Fig. 3.

Fig. 6 is a sectional elevation of the glue-applying mechanism of the machine.

Fig. 7 is a rear elevation of the mechanism 5 shown in Fig. 6.

Fig. 8 is a fragmentary section taken on line 8—8 of Fig. 6.

Fig. 9 is an enlarged, fragmentary view, partly in section and partly in elevation, of the braking 10 means for controlling rotation of the roll of paper or other material from which the sheet of material is drawn to produce the tubing, and of the roll shaft adjusting means.

Fig. 10 is a section taken on line 10—10 of 15 Fig. 9.

Fig. 11 is an enlarged, fragmentary sectional plan taken on line 11—11 of Fig. 3.

Fig. 12 is a fragmentary, sectional view illustrating part of the machine when the same is 20 arranged for producing square or rectangular type tubing.

Fig. 13 is a section taken on line 13—13 of Fig. 12 and looking in the direction indicated by the arrow.

Fig. 14 is a fragmentary rear elevation of a portion of the structure shown in Fig. 12.

Fig. 15 is an enlarged cross section taken on line 15—15 of Fig. 12.

In the drawings, wherein are shown for the 30 purpose of illustration, merely, two forms of the invention, A designates the improved machine generally. The machine A includes a rectangular frame or bed, which is made up of longitudinally extended channel elements 1 and transversely 35 extended channel elements 2, these longitudinally and transversely extended elements being suitably secured together to provide a rigid frame or bed structure. The longitudinally extended elements 1 and 2 are supported by suitable legs 40 3. Supported by and extended upwardly from the frame or bed of the machine is a superframe structure 4 made up of vertically disposed angle bars 5, secured adjacent to their lower ends to the bed of the machine, and horizontally arranged bars 6, 6', and 7 fixed to the vertical bars adjacent to the tops thereof and extended longitudinally and transversely of the machine.

Fixed to the opposed longitudinally extended elements 1 of the frame or bed of the machine A 50 is a pair of bearings 8 (Figs. 1, 2, and 3) which support a shaft 9 that is extended transversely of the machine. The shaft 9 supports a roll 10 of paper or other material from which a sheet of material S is drawn, said sheet of material 55

being passed through the tube-forming parts of the machine in a manner to be hereinafter described to produce tubing. The roll of material 10 is wound about a hollow core 11 (Fig. 2) through which the shaft 9 passes, said shaft having fixed thereon tapered elements 12 which are driven into the opposite ends of the core so as to frictionally engage same, after which said elements 12 are secured to the shaft 9 through the instrumentality of the set screws 12'. Thus the roll of material 10 is fixed to the shaft 9 for rotation therewith, the shaft rotating in the bearings 8 as the sheet of material S is drawn from said roll during operation of the machine. The sheet of material S passes about guide rollers 13 and 14, as shown to the best advantage in Fig. 3, the guide roller 13 being supported by the opposed longitudinally extended elements 1 and the guide roller 14 being supported by horizontally disposed elements 15 extended from the rearmost vertical elements 5 of the superframe structure of the machine to elements 32.

In order to provide for shifting the shaft 9 longitudinally of its major axis so that the roll of material 10 may be moved transversely of the machine to properly position said roll of material, the machine includes an adjusting screw 16 (Figs. 9 and 10). This adjusting screw is supported by a bracket 17 which is secured at 17' to one of the longitudinally extending elements 1 of the bed of the machine (Fig. 2), and has an outer portion 17" in which an aperture is formed through which the adjusting screw 16 passes. Adjacent to this outer portion 17" of the bracket a collar 18 is fixedly mounted on the adjusting screw 16, and at the extreme outer end of said adjusting screw a hand wheel 19 is fixed thereto. The hub of the hand-wheel 19 and the collar 18 contact with opposite faces of the outer portion 17" of the bracket 17, so that said adjusting screw is prevented from moving longitudinally, and also the inner end of the adjusting screw is provided with a smooth faced, reduced end portion 16' that extends into an aperture 20 formed in the longitudinally extended element 1 that supports the bracket 17, whereby said adjusting screw is supported for rotary movement by said longitudinally extended element 1 and the outer portion 17" of the bracket 17.

50 Fixedly mounted on the shaft 9 at a point above the adjusting screw 16 is a pair of spaced collars 21, and mounted on said shaft in a position between said collars is a clamping device 22. The clamping device 22 is comprised of an element 22^a and an element 22^b, said elements being provided with complementary curved seats which contact with the shaft 9. Also the element 22^b is provided with an extension 23 to which a bolt 24 is hingedly attached at 25, and the element 22^a is provided with a wing 26 having an open-end slot that receives the bolt 24. The bolt 24 has mounted thereon a wing nut 27 which is adapted to be screwed against the wing 26 of the element 22^a in order to move said element 22^a and 22^b into clamping engagement with the shaft 9. The element 22^b of the clamping device 22 is provided with a downwardly projected extension 28 which is provided with a screw-threaded opening 28' formed therethrough, through which the adjusting screw 16 extends.

70 When, in the use of the machine, it is desired to shift the shaft 9 longitudinally of its major axis so as to properly position the roll of material 10 transversely of the machine, the hand wheel 19 is rotated to rotate the adjusting screw 16, and

because the screw-threads of said adjusting screw are in engaging relation with respect to the screw-threads within the opening 28' formed through the extension 28 of the element 22^b, the shaft will be moved as desired. Also the clamping device 22 serves as a braking device for the shaft 9, as by tightening the elements 22^a and 22^b against the shaft, with the aid of wing nut 27, rotation of said shaft may be retarded in proportion to the pressure exerted against the shaft by the elements 22^a and 22^b.

Located adjacent to the guide roller 14 is an elongated glue receptacle which extends transversely of the machine, as shown in Figs. 1, 2, 3, 6, and 7. The glue receptacle 29 is supported for limited sliding movement on a pair of spaced angle elements 30, said angle elements being supported at their opposite ends by elements 31, which are fixed at their forward ends to the rearmost vertical elements 5 of the superframe structure of the machine and at their rearmost ends by members 32 which are fixed to the elements 6 and to the longitudinally extended elements 1 of the bed of the machine. The glue receptacle 29 is capable of being moved transversely of the machine through the operation of an adjusting rod 33 which is provided with an enlarged, screw-threaded portion 33'. This adjusting rod is supported for rotation by the opposed elements 31, as shown in Fig. 7, said rod being provided with a hand wheel 34 for operating same, and the glue receptacle having a downwardly extended element 35 which screw-threadedly engages the screw-threaded portion 33' of the rod 33. By rotating the adjusting rod 33 the glue receptacle 35 may be moved transversely of the machine to desired locations.

Secured to the glue receptacle 29 at opposite ends thereof are upstanding elements 35' which support at their upper ends a horizontally disposed angle element 36. The angle element 36 has fixed thereto by means of a set screw 37 a hinge member 38, to which a downwardly extended element 39 is hinged at 40. The element 39 is substantially L-shaped when viewed as illustrated in Fig. 6, inasmuch as said element includes an extension 39' which is extended at an approximate right angle with respect to the main body portion of said element. The element 39 is provided with a boss 41 which supports a pin 41' on which a glue-distributing disk 42 is mounted for rotation, the lower portion of the disk 42 being located within the glue receptacle, so that it passes through glue therein during rotation of the disk. Also, the peripheral edge of the disk 42 contacts with the sheet of material S as said sheet passes about the guide roller 14 (Fig. 3), whereby said disk is frictionally rotated by the moving sheet. The disk 42 has associated with it a glue scraper 43 which is so shaped as to embrace an edge portion of the disk, as shown to the best advantage in Fig. 8. The glue scraper includes a portion 44 which is slidably mounted on the portion 39' of the element 39, said portion 44 being formed about said portion 39' in embracing relation with respect thereto. The portion 44 of the glue scraper is provided with an outwardly extended lug 45 having a screw-threaded opening formed therethrough, which receives a screw-threaded portion of a rod 46, said rod being supported for rotary movement by a bracket 46' and having a weight 47 mounted thereon which is adjustable to different positions on the rod and is fixed in positions to which it is adjusted by a wing nut 47'. The weight 47 through the action of gravity

moves the peripheral face of the disk 42 into close contact with the sheet of material S, and by rotating the rod 46 the scraping edge 43^a of the glue scraper may be moved toward and from the peripheral edge of the disk so as to regulate the amount of glue applied to the sheet S by the disk 42.

The illustrated embodiment of the improved machine includes a glue reservoir in the form of an inverted bottle 48 which is supported by a suitable supporting structure 48^a. Leading from the inverted bottle 48 is a glue conductor 48^b whose discharge end is located within the glue receptacle 29 (Fig. 3), said conductor being provided with a valve 48^c which is adapted to control flow of glue from the inverted bottle 48 to the glue receptacle 29. In order to provide sufficient air pressure within the upper portion of the inverted bottle 48 to cause the glue to flow therefrom through the conductor 48^b, an air pipe 49 is employed (Fig. 2), this air pipe leading from a suitable source (not shown) of air under slight pressure to the upper portion of the inverted bottle, as shown to the best advantage in Fig. 3.

Supported by the superframe structure of the machine is a pair of heads 50 which are mounted for sliding movement on a pair of rods 51 and 51' which extend transversely of the machine, as shown to the best advantage in Figs. 2 and 3. The rods 51 and 51' are mounted in supporting elements 51^a (Fig. 2) formed on or fixed to the opposed side elements of the superframe structure 4, and also these rods pass through openings located adjacent to the lower ends of vertically disposed elements 52, which are secured at their upper ends to the element 6^a that extends longitudinally of the superframe structure 4 at the approximate transverse center of the machine (see Fig. 2). The heads 50 are relieved or cut away as indicated at 53 in Figs. 2 and 3 to provide cavities in which the lower portions of the elements 52 are received when the heads are brought together at the center of the machine. The heads 50 are shaped as shown to the best advantage in Figs. 2, 3, and 4; that is to say, each of said heads includes a portion 50^a which extends longitudinally of the machine which is provided with openings formed transversely therethrough through which the rods 51 pass, and at the rear end of said longitudinally extended portion 50^a each head includes a downwardly extended portion 50^b provided at its lower end with a downwardly and rearwardly inclined portion 50^c.

Fixed to the heads 50 are elongated tube-forming elements 54 which are in the general form of narrow, elongated plates that extend in substantial parallelism forwardly of the machine. The forward portion of the forming elements are substantially horizontal, or parallel with respect to the bed of the machine, and adjacent to their rearmost ends said forming elements include upwardly inclined portions 54^a, as shown to the best advantage in Fig. 3. From the rear ends of the upwardly inclined portions 54^a of the forming elements forwardly projected portions 54^b are extended, which at their forward ends are turned upwardly as indicated at 54^c in Fig. 3. The forming elements are secured to the heads 50 at their portions 54^c, and said forming elements contact with and are fixed to the inclined lower faces of the angular portions 50^c of said heads.

In order to assist in supporting the heads 50 for movement transversely of the machine, a rod 55 is provided. This rod, as shown in Fig. 4, is supported at its opposite ends by opposed, longi-

tudinally extended elements of the superframe structure 4 of the machine, and said rod extends through apertures formed through the upper portions of elements 56 which are secured to the heads 50 and extend upwardly therefrom. The elements 56 have associated therewith bracket elements 57 which are secured to the elements 56 at the points designated by the reference character 58. The elements 57 are inclined outwardly and downwardly, as shown in Fig. 4, and at the lower ends thereof vertically disposed portions 57' are provided through which openings are formed, the rod 51' being passed through said openings. It is obvious that the heads 50 are adequately supported for free movement transversely of the machine by the rods 51, 51', and 55, the bracket elements 57 assisting in maintaining said heads in their proper positions.

The means for adjusting the heads transversely of the machine comprises a rod 59 which is supported for rotation by oppositely disposed angle elements 60 (Fig. 4). The adjusting rod 59 is provided at one end with a hand wheel 61 to facilitate rotation of same, and said rod includes an enlarged intermediate portion 59' which is provided with right and left screw-threads designated, respectively, by the reference characters 59^a and 59^b. The intermediate portion 59' of the adjusting rod 59 passes through screw-threaded openings formed through the heads 50, the part of said intermediate portion provided with right-hand screw-threads being extended through the screw-threaded opening of one of the heads, and the part of said intermediate portion provided with left-hand screw-threads being extended through the screw-threaded opening of the other head. Obviously, rotation of the adjusting rod 59 will cause the heads 50 to move toward or from each other, depending on the direction of rotation of the adjusting rod, and because the tube-forming elements 54 are carried by the heads, like movement will be imparted to said tube-forming elements.

At the forward portion of the machine A a plate 62 is provided, which is supported by the opposed, longitudinally extended elements 4, and at opposite sides of this plate slotted elements 63 are fixed thereto which extend longitudinally of the forward portion of the machine. The slotted elements are secured adjacent to their opposite ends to the plate 62 by means of fastening devices 63', said slotted elements being raised slightly above the top face of the plate 62, as shown in Fig. 4, by suitable spacing members. Slidably secured to the slotted elements 63 are tube-forming members 64, the connections between said tube-forming members and said slotted elements being produced by bolts 65 which pass through the slots of said slotted elements and through apertures formed through the tube-forming members, as illustrated in Fig. 4. Obviously the end portions of the tube-forming members 64 may be moved longitudinally of the slotted elements 63 to desired positions, in which positions said members 64 may be secured by tightening the bolts 65. As shown to the best advantage in Fig. 11, the inner end portions of the tube-forming members 64 overlie the tube-forming elements 54, and said inner end portions of said tube-forming members 64 are maintained at their proper elevation by adjusting screws 66, which pass through screw-threaded openings formed through the tube-forming members and contact with and rest upon the top face of the plate 62. In order to main-

tain the adjustment of the adjusting screws 68, each thereof is provided with a lock nut 68'.

The improved machine includes guide pins 67 which under certain circumstances may be employed to aid in guiding the sheet of material into proper relation with respect to the tube-forming elements and members. Each of these pins is supported by a head 68 which is mounted for sliding movement on a pair of rods 69 which extend transversely of the machine and are supported by the longitudinally extended elements 1. The head 68 of each guide pin 67 is provided with a downwardly extended portion 70, which is provided with a screw-threaded-opening formed therethrough, and an adjusting rod 71 having right-hand screw-threads 71^a and left-hand screw-threads 71^b is extended through the screw-threaded openings formed through the portions 70, the right-hand screw-threads being extended through the portion 70 of one head 68 and the left-hand screw-threads being extended through the portion 70 of the other head 68. The adjusting rod 71 is supported for rotation by the opposed, longitudinally extended elements 1, and said adjusting rod is provided at one end with a hand wheel 72 which facilitates rotation of the adjusting rod. It is apparent that when the adjusting rod 71 is rotated the right and left-hand screw-threads thereof cause the guide pins to move toward or from each other, depending on the direction of rotation of said adjusting rod. Outward movement of the heads 68 with respect to each other is limited by a bar 68^a which is fixed to one of the heads and is provided with a longitudinally extended slot through which a pin 68^b carried by the other head extends (Figs. 2 and 11). When the end 68^c contacts with the pin 68^b, further continued movement of the heads 68 is prevented.

At the forward end of the machine a presser element 73 is provided which contacts with the top of the tubing as it moves from the machine. This presser element 73 is of elongated, tubular formation as shown in Figs. 1, 2, and 3, and it is attached to an arm 74 which is provided at its upper end with a slot 74'. The arm 74 is secured to the longitudinally extended element 6' of the superframe structure by a suitable fastening device 75 which passes through the slot 74' and is screwed into a screw-threaded aperture formed in said element 6'. Because of the slot 74' the arm 74 may be secured to the element 6' in various positions so as to position the presser element in different locations longitudinally of the extreme forward portion of the machine.

When the machine A is to be placed in operation, the sheet of material S is drawn through the machine by hand and the forward portion of the sheet is moved under the elongated tube-forming elements 54, the opposite side portions S^a of said sheet then being drawn upwardly about the opposite outer side edges of the tube-forming elements 54 and folded inwardly so that their inner edge portions are in overlapping relation, as shown at S^b in Figs. 5 and 11. The tube-forming members 64 are then positioned as shown in Fig. 11, where they contact with the top faces of the inwardly turned portions of the sheet of material S. The sheet of material S which is so drawn through the machine by hand has had a line of glue applied to it by the disk 42, and this line of glue, which is located between the overlapped edge portions of the sheet, causes said sheet portions to adhere to each

other. The forward end of the tubing is then drawn outwardly by hand to a suitable power-driven reel (not shown) with which the forward end portion of the tubing is associated, so that the tubing will be wound thereon when the reel is rotated. The reel is then placed in operation, and the sheet S is drawn by said reel from the roll 10 and is formed by the tube-forming elements 54 and the tube-forming members 64, and is then wound upon the reel. As already stated herein, the disk 42 applies a line of glue to the sheet S, and because the glue receptacle which supports said disk may be adjusted transversely of the machine by the adjusting rod 33, the disk may be adjusted to apply glue to any desired location on the sheet S. Also, as shown in Fig. 2, the angle element 36 is provided with a plurality of the hinge members 38, and the disk and its associated parts may be shifted from one thereof to another to obtain different positioning of the disk, or if desired in producing certain types of tubing, more than one glue-applying disk may be employed.

It will be noted that the machine shown in Fig. 1 includes a shaft 76 which corresponds with the shaft 9 already referred to herein. This shaft 76 has associated with it the same parts and elements described in connection with the shaft 9, and said shaft 76 is intended to support a second roll of material when tubing to be produced is of multi-wall or two-piece structure. When a second roll of material is used in producing tubing, the sheet drawn therefrom may pass over the guide roller 77 and then move over roller 14 with the sheet of material S drawn from the roll 10 into tube-forming relation with respect to the tube-forming elements 54 and the tube-forming members 64.

In Figs. 12, 13, 14, and 15 a structure is illustrated which is employed in producing tubing of the square or rectangular type. In producing such tubing an extra pair of tubing-forming elements 80 is employed. These forming elements 80 include narrow, elongated plate portions extending longitudinally of the forward portion of the machine at points slightly above the narrow, elongated plate portions of the tube-forming elements 54, as shown in Figs. 12 and 15. The tube-forming elements 80 are supported by rods 81, which are extended through openings formed through portions of the heads 58, said rods having downturned portions 81' (Fig. 12), the lower ends of which are inclined rearwardly and downwardly. The tube-forming elements 80 are secured to the downturned portions of the rods 81, and upwardly and rearwardly inclined portions of said elements contact with the lower faces of the downwardly and rearwardly inclined lower portions of said rods. Each head 58 is provided with a clamping screw 82 for clamping the associated rod 81 fixedly in position with respect thereto. Also, each rod 81 has clamped thereto a member 83 (Figs. 12 and 14) which is provided with a portion 83' that overlaps a side face of the associated head, and each portion 83' supports an adjusting screw 84 that contacts with the adjacent side face of the associated head 58. The members 83 are each provided with a slit 83^a to provide portions which clamp the associated rod 81, and these clamping portions are drawn into clamping contact with the rod by a screw 83^b.

In order to produce accurately formed square or rectangular type tubing the forming elements 80 must be precisely positioned with respect to

the forming elements 54, and such fine adjustment may be obtained by manipulating the adjusting screws 84 in contact with the heads 50 so as to rotate the rods 81 and thereby move the tube-forming elements 80 to the desired positions. The inner ends of the adjusting screws 84 are maintained in close contact with the heads 50 by contact of the paper with the tube-forming elements 80, hence rotation of the adjusting screws in either direction produces rotary movement of the rods 81 in one or the other direction. When the rods 81 have been adjusted to desired positions they may be clamped in such positions by the screws 82.

15 In producing square or rectangular type tubing plates 84 are employed whose inner edge portions are interposed between the narrow, elongated plate portions of the tube-forming elements 54 and 80, as shown in Fig. 15. These 20 plates are supported by arms 85 which are attached to said plates at their inner ends and are fixed at their outer ends to the slotted elements 63 by suitable fastening devices 85'. The pairs 25 of the arms 85 at opposite sides of the plates 84 are connected together by arms 86, and also said plates 84 are maintained at their proper elevations with respect to the plate 62 of the machine by means of adjusting screws 87 similar to the 30 adjusting screws 66 associated with the tube-forming members 64, said adjusting screws 87 at their lower ends contacting with and resting upon said plate 62 and being provided with lock nuts to maintain their adjustment.

35 The use of the machine in producing square or rectangular type tubing is substantially the same as in producing tubing of the type illustrated in Fig. 5, the only difference being that the opposite side edges of the tubing are folded inwardly as shown in Fig. 15 through the use of 40 the extra tube-forming elements 80 and the plates 84.

45 It is obvious, in view of the foregoing description of the improved machine disclosed herein, that tubing of the type shown in Figs. 5 and 15, and of various other types which need not be described in detail herein, may be made in various widths by merely adjusting the heads 50 transversely of the machine toward or from each other, this being accomplished by mere rotation of the 50 hand wheel 61 shown in Figs. 1 and 4. Thus the necessity that a number of sets of tube-forming elements for producing tubing of different widths be maintained on hand is entirely eliminated, and the operation of producing machine-made tubing is greatly simplified. Also, in the use of the improved machine, if the tubing being produced should run slightly wider or narrower than desired, the heads 50 may be adjusted while the machine is operating to correct the 60 error in the tubing width.

I claim:

1. A tube-forming machine including a pair of heads, means for supporting said heads for adjustment transversely of the machine, a pair of 65 vertically spaced tube-forming elements carried by each of said heads, means for adjusting one tube-forming element of each pair of tube-forming elements with respect to the associated tube-forming element, means for moving said heads 70 and said tube-forming elements transversely of the machine so as to provide for producing tubing of various widths, and tube-forming members co-operatively associated with said tube-forming elements.

75 2. A tube-forming machine including a pair

of heads, means for supporting said heads for adjustment transversely of the machine, a pair of vertically spaced tube-forming elements carried by each of said heads, means for adjusting one tube-forming element of each pair of tube-forming elements with respect to the associated tube-forming element, means for locking the adjustable tube-forming elements in adjusted positions, screw-threaded means for moving said heads and said tube-forming elements transversely of the machine so as to provide for producing tubing of various widths, and tube-forming members co-operatively associated with said tube-forming elements.

3. A tube-forming machine including a pair of 15 heads, means for supporting said heads for adjustment transversely of the machine, said means including spaced elements on which said heads are slidably supported, members secured to and extended from said heads, and an element slidably engaged by said members, tube-forming elements carried by said heads, means for moving said heads and said tube-forming elements transversely of the machine so as to provide for producing tubing of various widths, the last- 20 mentioned means including an element supported for rotary motion and provided with right-hand and left-hand screw-threaded portions which co-operatively engage said heads and are adapted to move same toward and from each other on 25 rotation of said screw threaded element, and tube-forming members co-operatively associated with said tube-forming elements.

4. A tube-forming machine including a pair of 30 heads, means for supporting said heads for adjustment transversely of the machine, said means including spaced elements on which said heads are slidably supported, members secured to and extended from said heads, and an element slidably engaged by said members, tube-forming 35 elements carried by said heads, means for moving said heads and said tube-forming elements transversely of the machine so as to provide for producing tubing of various widths, the last- 40 mentioned means including an element supported for rotary motion and provided with right-hand and left-hand screw-threaded portions which co-operatively engage said heads and are adapted to move same toward and from each other on 45 rotation of said screw threaded element, tube-forming members co-operatively associated with 50 said tube-forming elements, and means for adjustably securing said tube-forming members in place.

5. A tube-forming machine including a pair 55 of heads, means for supporting said heads for adjustment transversely of the machine, said means including spaced elements on which said heads are slidably supported, members secured to and extended from said heads, and an ele- 60 ment slidably engaged by said members, tube-forming elements carried by said heads, means for moving said heads and said tube-forming elements transversely of the machine so as to provide for producing tubing of various widths, the last- 65 mentioned means including an element supported for rotary motion and provided with right-hand and left-hand screw-threaded portions which co-operatively engage said heads and are adapted to move same toward and from each other on 70 rotation of said screw-threaded element, tube-forming members co-operatively associated with said tube-forming elements, and means including slotted members extended long- 75

tudinally of the machine for adjustably securing said tube-forming members in place.

6. A tube-forming machine including a pair of heads, means for supporting said heads for adjustment transversely of the machine, said means including spaced elements on which said heads are slidably supported, members secured to and extended from said heads, an element slidably engaged by said members, and brackets fixed to 5
10 said members and arranged in sliding relation with respect to one of said spaced elements, tube-forming elements carried by said heads, means for moving said heads and said tube-forming elements transversely of the machine so as to provide for producing tubing of various widths, the last-mentioned means including an element supported for rotary motion and provided with right-hand and left-hand screw-threaded portions which co-operatively engage said heads and are 15
15 adapted to move same toward and from each other on rotation of said screw-threaded element, and tube-forming members co-operatively associated with said tube-forming elements, said spaced elements being supported at their opposite ends and having a supporting member associated with each 20
20 thereof at its approximate center, said heads being provided with recesses which receive said supporting members when the heads are drawn inwardly to the limits of their movement.

7. A tube-forming machine including a pair of heads, means for supporting said heads for adjustment transversely of the machine, said means

including spaced elements on which said heads are slidably supported, members secured to and extended from said heads, an element slidably engaged by said members, and brackets fixed to 5
10 said members and arranged in sliding relation with respect to one of said spaced elements, tube-forming elements carried by said heads, means for moving said heads and said tube-forming elements transversely of the machine so as to provide for producing tubing of various widths, the last-mentioned means including an element supported for rotary motion and provided with right-hand and left-hand screw-threaded portions which co-operatively engage said heads and are adapted 15
15 to move same toward and from each other on rotation of said screw-threaded element, and tube-forming members co-operatively associated with said tube-forming elements, said spaced elements being supported at their opposite ends and having a supporting member associated with each 20
20 thereof at its approximate center, said heads being provided with recesses which receive said supporting members when the heads are drawn inwardly to the limits of their movement.
